CLAIM

The ornamental design for a meal tray retention packaging, substantially as shown and described.

DESCRIPTION

FIG. 1 is a front perspective view of a meal tray retention packaging, showing our new design.

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines are shown for the purpose of illustrating portions of the article that form no part of the claimed design. The surfaces absent of shading form no part of the claimed design.

1 Claim, 4 Drawing Sheets
